Frank N. S.

ATTORNEYS.

UNITED STATES PATENT OFFICE.

FREDERICK A. DIESTELKAMP, OF LOWELL, OREGON.

LOOSE-LEAF BINDER.

Application filed June 25, 1927. Serial No. 201,444.

My invention relates to improvements in loose leaf binders, and it consists in the combinations, constructions and arrangements hereinafter described and claimed.

5 An object of my invention is to provide a loose leaf binder which is extremely simple in construction, and which comprises a plurality of wires fashioned into separate rings and carried by a common support, each ring 10 being split so as to receive one or more leaves of a book.

A further object of my invention is to provide a device of the type described, in which the rings are so fashioned as to grip 15 more firmly when stress is applied to the book whereby the rings are prevented from becoming accidentally opened.

Other objects and advantages will appear in the following specification, and the novel 20 features of my invention will be particularly pointed out in the appended claims.

My invention is illustrated in the accompanying drawings forming a part of this application, in which

25 Figure 1 is a perspective view of the device;

Figure 2 is a side elevation of one of the rings showing it imbedded in the support;

Figure 3 is a view taken along the line 3—3 30 of Figure 2;

Figure 4 is a top plan view of another modified form of the device;

Figure 5 is a section along the line 5—5 of Figure 4;

35 Figure 6 is a view along the line 6—6 of Figure 5;

Figure 7 is a section along the line 7—7 of Figure 8 illustrating another modified form of the device and

40 Figure 8 is a section along the line 8—8 of Figure 7.

In carrying out my invention I provide a support 1, see Figure 1, which is preferably made of wood, because of the cheapness of the 45 material. The form of the device shown in Figures 1, 2 and 3 is the form that is the least expensive to manufacture of the various forms shown in the drawings. A plurality of wires 2 are fashioned into circles or rings 50 and have their ends inserted in openings 3 in the support 1. Figure 1 clearly shows how the short portion of the wire 2 projecting from the opening 3 is bent back upon itself and imbedded in the recess 4 for providing an 55 eyelet 5, and for preventing rocking and lon-

gitudinal movement of the ring in the opening 3. The opposite end of the ring 2 is hook-shaped at 6 and is removably receivable in the eyelet 5. The resiliency of the ring causes the hook 6 to bear against the side of the eyelet and any stress or strain placed upon the leaves 7 will cause the hook 6 to more firmly contact with the eyelet and thereby prevent the accidental opening of the ring.

As many rings as desired may be provided in the device and it will be noted that these rings open independently of each other, so that in case one ring or more accidentally opens, the other rings will retain the leaves 70 and prevent them from becoming mixed up. In standard loose leaf binders the rings are connected to a common opening device and if one ring opens all will open. The closing means on standard devices cannot withstand the stress of a large number of leaves pulling against the rings at the same time. In the present device the hooks 6 will more firmly engage with the eyelets when pressure is applied.

Figures 4, 5 and 6 show another modified form of the device in which the supporting back 13 has openings 14 therein for receiving a U-shaped portion 15, see Figure 5, of a ring 16. Part of the wire forming the ring 16 is shaped into an eyelet 17 and the end of the wire is received in an opening 18 in the support 13. The operation of this form of the device is identical to the operation of the form shown in Figures 1, 2 and 3 and therefore needs no further description.

Still another manner of securing rings to the support is shown in Figures 7 and 8. In this form of the device the ring 19 is first formed with a hook 20, an eyelet 21 and a zigzag portion 22. The rings are then placed in a mold, not shown, and metal is flowed into the mold for forming a supporting back 23. The metal will cover the zigzag portion 22 and will also cover the end 24 of the eyelet 21. In this way the rings 19 are securely imbedded in the support 23 and the zigzag portion 22 not only prevents the ring from rocking in the bore 25, but also from longitudinal movement in the bore. It is obvious that the rings 19 may be riveted or soldered to the supporting back 23, if desired, and then the hook 20 may be received in an opening in the back 23.

Although I have shown and described 110

various embodiments of my invention, it is to be understood that the same is susceptible of various changes and I reserve the right to employ such changes as may come within the 5 scope of the appended claims.

I claim:

1. In a loose leaf binder a plurality of rings having a zigzag portion and a back for said rings formed by flowing metal over the 10 zigzag portions for enclosing these portions.

2. In a loose leaf binder, a support, split rings carried by said support, one end of each ring being fashioned into an eyelet, the end of the eyelet being embedded in said support, whereby said support forms a part of the 15 eyelet, the other end of each ring being removably receivable in the eyelet associated therewith.

FREDERICK A. DIESTELKAMP.
